UNITED STATES PATENT OFFICE.

GEORGE HENRY WILDSMITH, OF LEEDS, ENGLAND.

DESIGN FOR A GAME-BOARD.

SPECIFICATION forming part of Design No. 23,360, dated June 12, 1894.

Application filed May 9, 1894. Serial No. 510,663. Term of patent 14 years.

To all whom it may concern:

Be it known that I, GEORGE HENRY WILDSMITH, a subject of the Queen of Great Britain, residing at Leeds, in the county of York, England, have invented a certain new and original Design for Game-Boards; and I do hereby declare the following to be a full, clear, and exact description of the invention, such as will enable others skilled in the art to which it applies to make and use the same.

In the accompanying drawing my said design is illustrated.

The leading features of said design consist in a surface of approximately rectangular outline having openings A arranged at intervals in the same and raised portions B of the surface alternating therewith. These raised surfaces have round or scalloped outlines. Other raised surfaces C C' D D' are arranged as borders in pairs at the top and bottom, respectively, of the design leaving in the middle of the top and the middle of the bottom an opening between the members of each pair, where the ordinary surface appears. The various openings A above mentioned are indicated by different numerals marked on the surface above them and representations of animal figures are marked or printed on the surface below them. Thus as shown under

the upper left hand opening is the figure E 30 of a lion; under the upper right hand one is the figure F of an elephant; under the next lower left hand opening the figure G of a wolf; under the next lower right hand opening the figure H of a bear; in proximity to 35 the next two lower holes are the figures I of crocodiles with the water J and marsh vegetation K of their habitat; under the two next lower openings are the figures of a buffalo L and a lion M; and under the lowest two openings A are the figures of a snake N and a fox O. Figures P of trees and other vegetation are arranged at several points on the main surface, and the raised surfaces aforesaid are colored green and mottled to give the appearance 45 of vegetation.

Having thus described my invention, what I claim, and desire to secure by Letters Patent, is—

The design for a gameboard as herein shown 50 and described.

In testimony whereof I affix my signature in presence of two witnesses.

GEORGE HENRY WILDSMITH.
